DESIGN FOR A CASING FOR METERS

Application filed January 20, 1930. Serial No. 34,198. Term of patent 14 years.

To all whom it may concern:

Be it known that we, WALTER G. MYLIUS and BERT G. LA BAR, citizens of the United States, residing at Summit and Union, respectively, in the county of Union and State of New Jersey, have invented a new, original, and ornamental Design for Casing for Meters, of which the following is a specification, reference being had to the accompanying drawing, constituting a part hereof.

The figure of the drawing illustrates a cas-

ing for an electrical instrument showing our new design for casing for meters.

We claim:—

The ornamental design for a casing for meters substantially as shown.

In testimony whereof, we have hereunto subscribed our names this 9th day of Jan., 1930.

WALTER G. MYLIUS.
BERT G. LA BAR.
